UNITED STATES PATENT OFFICE.

JAMES G. CUTLER, OF ROCHESTER, NEW YORK.

LETTER-BOX CONNECTION.

SPECIFICATION forming part of Letters Patent No. 390,347, dated October 2, 1888.

Application filed April 18, 1887. Serial No. 235,144. (No model.)

To all whom it may concern:

Be it known that I, JAMES G. CUTLER, a citizen of the United States, residing at Rochester, Monroe county, New York, have invented 5 certain Improvements in Letter-Box Connections, of which the following is a specification, reference being had to the accompanying drawings.

My invention relates to certain improvements on the letter-box connections or mail-chutes described in Patents No. 284,951, of September 11, 1883, and No. 336,038, of February 9, 1886, which improvements are described and illustrated in the following specification 15 and accompanying drawings, the novel features thereof being specified in the claims annexed to the said specification.

My improvements in letter-box connections are represented in the accompanying drawings, in which—

Figure 1 is a front view of a portion of the tube. Fig. 2 is a central vertical section of the same. Fig. 3 is an elevation of the upper portion of one section of the tube. Fig. 4 is a transverse section of the same on the line 4 4, Fig. 3. Fig. 5 is a transverse section on the line 5 5, Fig. 1. Fig. 6 is an elevation of a portion of the base. Fig. 7 is a vertical section of the same on the line 7 7, Fig. 6.

30 My improved letter-box connection consists of a vertical tube extending through the different stories of a building, which tube is made in sections connected by suitable joints and attached to a wall or other support by bands surrounding the joints. The tube or chute is provided at proper intervals with openings for the insertion of letters or other mail and terminates at the bottom in a suitable receptacle or mail-box.

40 In the accompanying drawings, A represents one of the removable sections of my improved mail-chute, and A' the next higher section. Each section consists of a sheet-metal tube, L, bent to form three sides of a rectangle, and 45 having a glass front, B, inserted in the fourth side and secured to the inwardly-projecting edges i of the sheet-metal tube by the clamps C C. The front of the chute is preferably made of heavy plate-glass. The glass front 50 permits the inspection of the interior of the

tube, so that the descent of the mail matter may be readily observed and the position of any accidental obstruction in the tube may be located. The clamps which secure the front B to the sheet-metal tube L are composed of 55 two strips of metal of a form substantially such as shown at C in the sectional views, Figs. 4 and 5, secured together by a line of rivets. The strip a on the outside of the tube is preferably formed of sheet-brass and bent as 60 shown, so that the outer edges of the curved portions will firmly clamp the glass and metal against the edges of the inner strip, b, which are preferably slightly bent toward the outside, as shown in the drawings, so as to make 65 their edges rounded and smooth, and thus prevent anything from catching between the glass or the metal and the inner strip, b, of the clamp. If desired, projections or lugs may be stamped into the sheet metal of the tube at f, 70 Figs. 3 and 4, which fit the curved portion of the clamp a, preventing any motion sidewise, and keeping the clamps engaged with the metal and the parts of different sections in correct line with each other.

75 The parts of the clamp C are secured together before setting up the apparatus, and are slid on from the end of each section. The glass front is then slid into place between the inner edges of the clamps. The sheet-metal 80 tube is provided on the front side with the inwardly-projecting flanges i, Figs. 3 and 4, which project between the outer edges of the clamp-strips a and b. The outer clamps, a, are provided with longitudinal channels, as shown 85 in the sectional views, whereby they are adapted to receive the flanges i and the outer edges of the glass front B, while at the same time they serve to give a finished or ornamental appearance to the chute. The clamps are sufficiently elastic to hold the flanges i and the glass with a firm pressure when inserted therein. The inner and outer clamp-strips are secured together by the rows of rivets or bolts k, Figs. 3 and 4, care being taken that the inner ends of 95 the rivets are countersunk so as to come flush with the inner surfaces of the clamp-strips b, to avoid any projections on which mail matter might lodge. The lugs or projections f, which serve to hold the clamps on the flanges and 100

in line with the tube, may be made in any suitable way—such, for instance, as that shown in the drawings—by bending outward a portion of the metal of the flange by a punch. 5 In Fig. 4 it will be observed that a space, *j*, is left between the edges of the glass front and the inner surface of the channel in the outer clamp, *a*, the object of such construction being to permit the use of glass of slightly varying widths.

The sections of my improved mail-chute are provided at the top and bottom with the bands *E E'*, encircling them and riveted or otherwise secured to the metal of the tube. 15 The bands *E E'* are fastened by the screws *g g* to the plate *F*, which is screwed or otherwise attached to the wall or other suitable support. The plate *F* is provided with recesses *m*, Fig. 3, on its face, into which fit corresponding lugs 20 on the rear sides of the bands *E E'*. The plates *F* are permanently secured to the wall, and the bands on the ends of the sections of the letter-chute are screwed thereto at *g*, Fig. 1, so that any one of the sections may be removed independently of the others when access to the interior of the tube is desired, and can be replaced in its exact former relation with the other sections. Any one of the sections, with the bands at its upper and lower 25 ends, may be removed by taking out the screws *g*, by which the lugs *r* at the rear corners of the bands are secured to the plate *F*. I prefer to cover the outer portion of the bands *E E'* with a plate or band of burnished 30 or ornamental metal, *H*, so as to conceal the joint between the bands, such ornamental covering being attached by screws *n*, Fig. 1. Between the ends of the glass fronts of the adjacent sections is placed the bar *G*, Figs. 1 and 40 2, which is attached to the band *E'* at the lower ends of the sections. The inner surface of the bar *G* is beveled slightly, as represented in Fig. 2, so that its lower edge projects inward into the tube a short distance beyond the glass of the next lower section, so 45 as to prevent any mail from lodging thereon. The band *E* is recessed on the inner side to receive the ends of the bar *G*, which extends the whole width of the tube *L*, the inner surface 50 of the bar being thickened at the ends to correspond with the inner clamp, *b*, so as to avoid any ledges or projections which might obstruct the descent of mail matter in the chute.

55 The bar *G* is indicated by dotted lines in Fig. 5. The bar serves to carry the weight of the glass and prevent its displacement.

As indicated in the drawings, the bands *E E'* may be cut away to reduce the amount of metal in them, the recess thus formed being 60 covered by the band *H*.

In Figs. 1 and 2 I have shown the mailing-section *D*, which is located in the front of the tube at a suitable height from the floor. The 65 section *D* is a casting inserted in the front of the tube in place of a portion of the glass. The outer portion of the casting *D* projects from

the face of the tube, and is provided with an opening at *c* for the insertion of mail, which passes into the tube through the mailing-section. The casting is preferably provided with flanges *p* at its top and bottom, which overlap the glass, as shown in the sectional view, and at its sides are flanges of the same thickness as the glass used in the chute, upon which the 70 clamps *C C* bear, holding the section *D* firmly in place. A swinging gate, *s*, is pivoted in the casting *D*, as shown in the section, Fig. 2, and is normally open, affording a free passage into the chute at *c*. The distance between the front 75 of the mailing-section and the lower portion, *s'*, of the gate at *e* is so proportioned that when a piece of mail matter so large as to be liable to clog the tube is inserted through the opening *c* it comes in contact with the lower end 80 of the swinging gate at *e* and moves the gate into the position represented by the dotted lines in Fig. 2. The upper end of the gate *s* is turned outward, forming a lip, *t*, as shown in the section, and moves across the opening *c* 85 when the lower end is forced into the tube by a package of excessive size, thus clamping the upper end of the package at *c* and preventing its insertion into the tube. The clamping-edge 90 *t* of the gate *s* is toothed or notched, (not 95 shown,) so as to give a firmer grasp on the object which it seizes. This device is especially useful in preventing the insertion of loosely-folded newspapers, which expand after being forced through the orifice *c*. The swinging gate 100 *s* is pivoted at *d*, Fig. 2, in the projecting sides of the mailing-section *D*.

It will be observed that the mailing section inclosing the gate *s* projects outward entirely beyond the front side of the tube, so that the 105 free descent of mail matter in rear of the gate is permitted even if the latter should be clogged by the introduction of a newspaper or other article too large to pass by the lower end of the gate. It will also be observed that the orifice *c* 110 is of restricted dimensions and that the gate consists of a solid plate extending the whole width of the mailing-section, so that the mail matter may act on it at any point below the line of the pivots *d d*.

I hereby disclaim the construction shown in the patent of Wittram, No. 91,583, June 22, 115 1869.

The construction of the base of my improved mail-chute is represented in Figs. 6 and 7. 120 Around the lower portion of the tube, just above each floor through which it passes, is placed the base *P*, surrounding the tube on the front and sides, but open at the back or next the wall or support. The base may be formed of one or more pieces and ornamented in any preferred manner; but I prefer to make it in two sections, *P* and *P'*, the upper of which is attached to the lower, so as to be readily detached therefrom, while the lower is secured to the floor or a block, *u*, fastened thereto. The lower end of the section of the mail-chute next above the floor is provided with a band, *E'*, attached to a plate, *F*, secured to the wall, in

all respects like the construction already described; but the connection through the floor to the uppermost section in the next story of the building is made by a plain metallic pipe, 5 R, Fig. 7, of the same dimensions as the tube L. The floor-section R may be readily adapted in its length to the distance between the lower section on one floor and the highest section on the next, so that while the sections with the 10 glass fronts are all made of uniform length, by varying the length of the floor-section, the apparatus is adapted to being readily put up in buildings having stories of varying heights. The floor-section R is provided with bands at 15 its upper and lower ends, by which it is secured to the plates F.

I claim—

1. The combination, with a mailing-tube consisting of a series of independently-removable sections, of the bands E E', surrounding the ends of the sections and removably attached to the plate F, secured to the wall or other support, whereby the removal of any one of the sections is permitted without disturbing 25 the remaining sections, substantially as described.

2. The combination, with the adjacent sections of a mailing-tube, of the plate F, attached to the wall or other support, and the separate 30 bands E E', surrounding the ends of the tubes and removably secured to the plate F, substantially as described.

3. The combination, in a mailing-tube, of a series of independently-removable sections 35 consisting of the sheet-metal tube L, glass front B, clamps C C, and band E' around the lower end of the section, provided with bar G, arranged to support the glass, substantially as described.

4. The combination, with the mailing-tube

provided with a glass front secured thereto by the removable clamps C C, of the mailing-section D, substantially as described.

5. The combination, with the mail-chute A, of the mailing-section D, provided with a restricted mail-orifice, c, at its top, projecting from and located in front of the chute, and the pivoted plate constituting the gate s, having an outwardly-projecting lip, t, at its upper end, whereby the insertion of mail matter of excessive dimensions is prevented, while the chute is left unobstructed for the descent of mail matter from above in rear of the gate, substantially as and for the purposes set forth. 45

6. The combination, with a mailing-tube 55 formed of sheet metal and provided on one side with inwardly-projecting flanges, of the glass front B, attached to the said flanges by the clamps C C, and the mailing-section D, provided with orifice c, for the introduction of 60 mail matter into the tube, and with projecting flanges, whereby the mailing-section is adapted for attachment to the tube by the clamps which hold the glass front, substantially as described.

7. The combination, with the sheet-metal 65 tube-section L of a mail-chute having inwardly-projecting flanges i, of the glass front B, attached to the flanges by clamps with its inner surface in substantially the same plane as the inside of the flanges, as and for the purposes 70 set forth.

8. The combination, with the sheet-metal tube L, having inwardly-projecting flanges i, of the glass front B and the clamps C C, consisting of the outer and inner plates, a and b, 75 substantially as described.

JAMES G. CUTLER.
